[57] CLAIM

The ornamental design for a wind damper, as shown and described.

DESCRIPTION

FIG. 1 is a rear perspective view of a wind damper showing our new design;

FIG. 2 is a front elevational view thereof;

FIG. 3 is a top view thereof;

FIG. 4 is a bottom view thereof;

FIG. 5 is a side view thereof;

FIG. 6 is a rear view thereof;

FIG. 7 is a detail exploded view thereof; and,

FIG. 8 is a perspective view thereof, showing the device on its intended environment, the broken-line showing of environmental structure is for illustrative purposes only and forms no part of the claimed design.
